UNITED STATES PATENT OFFICE.

FESTUS S. RAND, OF PROVIDENCE, AND GEORGE N. TAYLOR, OF EAST PROVIDENCE, RHODE ISLAND, ASSIGNORS TO UNIVERSAL WINDING COMPANY, OF PORTLAND, MAINE, A CORPORATION OF MAINE.

WINDING-MACHINE.

1,205,565.

Specification of Letters Patent. Patented Nov. 21, 1916.

Application filed March 13, 1914. Serial No. 824,490.

To all whom it may concern:

Be it known that we, FESTUS S. RAND and GEORGE N. TAYLOR, citizens of the United States, residing at Providence and East Providence, respectively, in the county of Providence and State of Rhode Island, have invented certain new and useful Improvements in Winding-Machines, of which the following is a specification.

10 Our invention consists of improvements in winding machines and relates particularly to "friction" or "drum" winders in which the yarn-cop or thread-package is rotated through frictional contact of its surface with the periphery of a drive-roll or drum.

Our improvements are directed principally to the starting and stopping mechanism of the machine, the object being to provide a more effective and positive control 20 over the winding-spindle whereby the rotation of the cop can be more easily and quickly arrested either upon the breakage or exhaustion of the yarn or for other cause.

A further object of our improvement is 25 to simplify the structure of the machine, to render it more efficient and durable in use and to facilitate its manipulation and control.

The method and means for carrying out 30 these improvements are fully described in the following specification, illustrated by the accompanying drawings, in which like reference characters designate like parts.

In the drawings: Figure 1 is a side elevation of our improved machine with the gear-casings shown in section to illustrate the driving connections; Fig. 2 is an end elevation of the same; Figs. 3, 4 and 5 are detail views of portions of the stopping- 40 mechanism for the winding-spindle; Fig. 6 is a detail view of the means for releasing the yarn from the thread-guide upon the stopping of the machine; and Fig. 7 is an enlarged view of the operating and detent- 45 devices for the stopping-mechanism, part sectional on the line X—X of Fig. 1, looking in the direction indicated by the arrow x.

Referring first to Figs. 1 and 2, B designates the main frame of the machine which 50 is provided with bearings for two horizontal shafts C and D. On the lower shaft C is fixedly mounted a usual form of traverse-cam

C', adapted to actuate the traversing thread-guide E; and held fast on the upper shaft D is the drive-roll or drum D' which rotates the yarn-cop or package through peripheral contact therewith. The winding-spindle F which receives the cop-tube f or other shell or holder on which the package is wound is arranged above the drive-roll D' and rotates in an end-bearing G.

Referring to Fig. 3, the spindle-bearing G is formed with two arms g, g' pivotally mounted on a slide or carriage H which is adapted to move upwardly on a vertical rod 65 h mounted on the frame B. Preferably, the carriage H is formed with two bearings h', h², see Fig. 7, fitted to slide on the rod h and spaced at some distance apart to provide against their cramping on the rod and preventing a free movement of the carriage. Extending horizontally through a hub h³ of the upper bearing h' of the carriage H is a fixed rod or stud h⁴ on which is pivotally mounted the hubs g², g³ of the spindle-bearing arms g, g'. On the outer end of the rod h⁴ is a collar I held in place by the set-screws i, i which are screwed against the bottom of a recess or slot h⁵ in the rod, see Fig. 7. The collar I is provided with an 80 arm or extension i' which carries a brake-shoe J pivoted on the pin j and adapted to engage a wheel or disk J' fast on the winding-spindle F. Preferably, the shoe J is formed with one or more V-shaped slots or 85 openings j', see Fig. 3, adapted to impinge upon the beveled sides of the correspondingly-shaped flanges j² of the wheel J'.

Figs. 2 and 7 illustrate the bearing G in position with the winding-spindle F directly 90 over the axis of the drive-roll D' so that the cop-tube f on the spindle bears on the periphery of the roll. This is the normal relation of the parts at the beginning of the winding, and as the yarn builds up on the cop-tube f the spindle F will rise with the increase in diameter of the package causing the carriage H to slide upwardly on the rod h. The spindle F is normally carried down into position to engage the periphery 100 of the cop-tube f with the drive-roll D' through the effect of gravity, and preferably weighted means are provided for applying the required pressure to the carriage H to

maintain the surface of the package in frictional contact with the roll. This portion of the machine, however, forms no part of the present invention and is therefore not here shown or described in detail.

The bearing G which carries the winding-spindle F, as before stated, is supported by the arms g, g' to oscillate about the rod h⁴ and is operated manually from a handle or lever K extending horizontally from the side of its hub g². Extending from the opposite side of the hub g² is a horizontal arm g⁴ to the end of which is fastened a coiled spring g⁵, see Figs. 4 and 7. The opposite end of the spring g⁵ is held by a pin g⁶ driven into the side of the carriage H. The tendency of the spring g⁵ is to rock the bearing G in the direction indicated by the arrow 2, Fig. 4, to carry the spindle away from the drive-roll D' so that the cop-tube f or its surrounding package, as the case may be, will be freed from the roll whereby its rotation can be arrested. As the spindle F is swung away from the drive-roll D' in this manner the force of the spring g⁵ will carry its brake-wheel J' into engagement with the shoe J to cause a friction between the two to check the rotation of the spindle.

Referring again to Figs. 1 and 2, the thread-guide E takes the form of a relatively thin sheet-metal arm supported at its base on a traverse-slide or carriage E'. The upper portion of the guide E is curved inwardly around the face of the drive-roll D' to bring its end e in close proximity to the point of contact of the cop-tube f on the roll. As shown more particularly in Fig. 7, the upper extremity of the guide E is bent or curled upwardly at e' and rounded off along its edge, see Fig. 1, to provide a slight crown on its top. In the center of this crowned portion is a notch or depression e² which serves as a guiding-eye for the yarn y. The traverse-slide E' on which the guide E is mounted is provided with bearings e³, e³ fitted to slide on two horizontal rods e⁴, e⁴ extending between the sides b, b' of the frame B. Passing through the slide E' is a stud e⁵ which projects downwardly through a second slide-plate or runner E² and carries a roll e⁶ at its lower end adapted to engage the groove c in the cam C'. The plate E² slides in parallel grooves l, l formed in the horizontal sides of a traverse-frame L, the latter being constructed with depending legs l', l' straddling the cam C' and formed with hubs l², l² mounted on the cam-shaft C.

In our previous application for patent, Serial No. 813,013, filed January 19, 1914, we have disclosed a mechanism for oscillating the frame L about the axis of the shaft C during the reciprocation of the thread-guide. The purpose of this device is to intermittently shift the roll e⁶ in the cam-

groove c to effect an increment and decrement of movement of the thread-guide throughout the winding. This action causes an interruption of the consonance of movement between the thread-guide and winding-spindle and serves to break up the regularity of the winding to prevent what is termed "ribbon-winds". For winding certain forms of packages, however, particularly for winding in multiple, where the material is to be delivered by unrolling, this breaking up of the wind is not so important and the mechanism referred to can be dispensed with. Therefore, for the sake of simplification in the drawings we have preferred not to show this arrangement in the present application. To adapt the machine for use without this traverse-changing device it is only necessary to hold the traverse-frame L in its upright position, as illustrated in Fig. 2, and the simplest means for accomplishing this consists of a screw l³ extending through the side b of the frame B, see Fig. 1, and engaging a suitable hole l⁴ in the leg l' of the frame.

In winding machines of this type it is not usual to provide means for stopping the operation of the thread-guide when the rotation of the winding-spindle is arrested. That is to say, in drum-winders the general practice is to allow the thread-guide to continue to oscillate even after the winding-spindle has stopped. When the rotation of the winding-spindle is arrested on account of the breaking of the yarn, the continued reciprocation of the thread-guide very often interferes with the piecing up of the ends. If one end still remains in the guide it will be carried back and forth and is liable to be twitched out of the operator's hand while he is tying up, or in some cases the yarn might be strained or broken. To obviate this condition and make it more convenient for the operator to piece up the ends when the yarn is broken or exhausted during the winding we have devised a simple and efficient means for freeing the yarn from the thread-guide whenever the rotation of the cop is arrested. This consists essentially of a tilting lifter-device or plate M arranged above the curved portion of the thread-guide E with its edge m normally lying on top of the latter, see Fig. 7. The opposite edge of the plate M is turned down at m' and overlaps the upper edge of a vertical guard-plate M' which is fastened to a portion of the frame B by the screws m², m² and extends along the front of the drive-roll D'. The lifter-plate M may be supported in any suitable manner to adapt its edge m to be tilted upwardly to raise the yarn y out of the guide-eye e², and as here shown it is provided with ears m³, one at either end, pivoted on suitable pins m⁴ held

in similar ears m^{10} bent around from the ends of the plate M'. The two plates M and M' serve as a shield or guard to prevent the yarn from falling down and becoming caught on the guide or entangled in the other operating parts of the machine.

Referring to Figs. 6 and 7, the lifter-plate M is operated through an arm m^5 which carries a screw m^6 adapted to be engaged by an element of the stopping-mechanism of the machine as later described. Preferably the arm m^5 is formed of sheet-metal and secured to the plate M by the rivets m^7 or through any other suitable means. Its downwardly extending portion m^8 is bent back on itself at m^9 and the screw m^6 is threaded through both thicknesses of the metal. The two overlapping portions m^8 and m^9 are sprung 20 slightly apart so that they bind on the screw m^6 and serve as a friction locking-means therefor in lieu of a check-nut, while allowing adjustment of the screw in the arm.

The present machine is adapted to be operated in series or "gangs," that is, with a plurality of units all mounted on a common table or bed and driven from a single main driving-shaft. Referring to Fig. 1, the driving-shaft N here shown extends between the two shafts C and D at right-angles thereto and carries a spiral gear N' meshing with a similar gear N² on the shaft D. On the outer end of the shaft D is a cone-pulley O from which rotation is transmitted to an oppositely-arranged cone-pulley O' by means of a belt o. The pulley O' is mounted fast on a shaft o' which rotates in a bearing p formed as a part of a gear-casing P. The gear-casing P is supported on the end of the cam-shaft C and incloses a gear p' fast on said shaft and arranged to mesh with a pinion p² on the inner end of the pulley-shaft o'. The main driving-shaft N drives the shaft D through the gears N', N² and rotation is imparted by the pulley O to the pulley O' and transmitted thence through the shaft o' and gears p', p² to the cam-shaft C. As more particularly shown and described in our pending application before referred to, the belt o is arranged to be shifted longitudinally of the pulleys O, O' to alter the speed ratio between the drive-roll and cam throughout the winding. The purpose of this device is to regulate the change in the "wind" as the cop increases in diameter, but as this arrangement of the mechanism forms no part of the present invention it will not be here described in detail.

Fastened to the front end b of the frame B is a bracket Q which supports the tension-device Q' for applying tension to the yarn as it delivers to the winding-spindle. The machine is here shown as adapted to wind in multiple, that is, with several ends

up, and for this purpose a plurality of tension-devices are employed. These may be of any approved form and as illustrated in the drawings consist of three pairs of the usual grid-members q, q between which the yarns y draw. The members q are mounted on frames Q² attached to the bracket Q and are provided with suitable means, not here shown, for pressing them against the yarn. From the tension-devices Q' the yarns lead 70 through guide-eyes r, r, etc., carried at the ends of tilting drop-wires R. The drop-wires R are pivotally mounted on a rod r', see Figs. 1 and 7, which extends through bearings in a frame R'. The frame R' is secured to an upright member B' which is either formed as a part of or attached to the main frame B of the machine. Also mounted in bearings on the frame R' is a cross-rod r² on which is pivotally supported 75 a wire bail R². The bail R² is formed with legs r³ having their ends pivoted on the rod r² and a cross-member r⁴ adapted to be engaged by the ends of downwardly reaching extensions r⁵ on the drop-wires R. A rod 80 r⁶ extends across the front of the frame R' above the lower ends of the drop-wire R and serves to limit the upward movement of the latter under the action of the tension on the yarns y. From the drop-wires R the several yarns lead up over a longitudinal rod R³ held in a bearing b² on the frame-member B' and thence are drawn through the eye e² in the thread-guide E to the winding-spindle F.

Pivotaly mounted on a screw s secured in the frame-member B' is a fan-shaped lever S, see Fig. 7, one arm s' of which is provided with a hole into which is inserted the end of a wire r⁷ which forms an extension of the inner leg r³ of the bail R². A second lever S' is mounted on the screw s on the inside of the lever S and has a downwardly extending arm s² to which is connected one end of a wire link t. The opposite end of the link t is hooked into a depending pawl-member T which is pivoted on a pin t' at the end of a lever T'. The lower hooked end t² of the pawl T is adapted to be engaged by the ratchet-teeth t³ of a wheel or disk T² which is fixedly mounted on the cam-shaft C and rotates therewith in the direction indicated by the arrow 3, Fig. 7. A pin t⁴ in the lever T' is adapted to be engaged by a projection or shoulder t⁵ on the pawl T to limit the swinging movement of the latter toward the wheel T². The two levers S, S' are connected by a screw s³ reaching through a slot s⁴ in the lever S and screwed into the lever S', a washer s⁵ being placed under the head of the screw. By loosening the screw s³ the relation of the arm s' on the lever S to the arm s² of the lever S' can be altered to adjust the position of the pawl T in relation to the 100 105 110 115 120 125 130

teeth t^3 on the wheel T^2 . The lever T' , on which the pawl T is pivoted, is mounted on a stud t^6 screwed into the frame-member B' and is formed with a laterally extending arm t' adapted to engage the side of a vertical member or bar U which forms a part of the controlling-mechanism for the winding-spindle F .

The bar U is pivotally supported at its upper end by a stud u screwed into the end of the arm g^4 which controls the movement of the spindle-bearing G . Substantially midway of its length its side is engaged by a plunger-pin u' slideable in a bore u^2 of the frame B , see Fig. 6. A coiled spring u^3 acts to force the plunger u' against the bar U , tending to swing it in the direction indicated by the arrow 4, Fig. 7. Extending parallel with the bar U is a second vertical bar V fastened at its upper end to a lug h^6 on the side of the carriage H . The bar V is adapted to slide up and down with the movement of the carriage H and is guided at its upper end in a bearing b^3 on the frame-member B' . At the lower end of the bar V is a guide-piece v , see Figs. 1 and 5, held in place by the screws v' , v^2 and projecting through a slot b^4 in the frame-member B' in which it is adapted to slide. Pivoted above the bearing b^3 is a dog-lever W which is adapted to impinge against the sides of the bar V to resist the downward movement of the latter and thereby the movement of the carriage H . The dog-lever W is mounted on a pin w driven through the ears b^5 which project upwardly from the bearing b^3 . The hole w' through which the pin w extends is preferably of greater diameter than that of the pin so as to provide a floating bearing for the lever W . One end of the lever W is formed with an opening w^2 through which the rod V passes and the opposite sides thereof are formed with convex faces w^3 , w^3 as shown in Fig. 7. The opposite end of the lever W is formed with a finger-piece w^4 and is operated upon by a coiled spring w^5 held in a pocket b^6 in the bearing b^3 . The tendency of the spring w^5 is to tilt the lever W to cause it to cramp against the sides of the bar V to resist the downward movement of the latter. The purpose of this arrangement is to prevent the winding-spindle F from moving downwardly toward the drive-roll D' after it has once been forced away therefrom by the growth of the winding, the object being to prevent undue movement or jumping of the spindle liable to be caused by irregularities on the surface of the cop. When it is desired to set the spindle in relation to the drive-roll the dog-lever W is released by pressing downwardly on the finger-piece w^4 and the bar V is then free to slide through the opening w^2 in its opposite end.

To maintain the spindle F in place above the drive-roll against the force of the spring g^5 acting on its bearing G the two bars U and V are locked together against the longitudinal movement of one with respect to the other by means of a detent-device shown particularly in Fig. 7. Set into the side of the bar U and held in place by the screws u^4 is a block U' formed with a shouleder projection or latch u^5 . The lower edge of the latch u^5 is adapted to engage with an opposite detent-shoulder v^3 formed on a detent-block V' set into the side of the bar V and held in place by the screws v^4 , v^4 . Below the shoulder v^3 is a beveled face or incline v^5 on which the edge of the latch u^5 rides after being released from the detent-shoulder. Above the shoulder v^3 is a projection v^6 having an inclined face v^7 against which the upper end of the latch u^5 bears, the purpose of this being explained hereinafter in connection with the operation of starting the machine.

Fastened to the front face of the bar U by the screws u^6 is a sheet-metal plate U^2 formed with an extension u^7 overlapping the side of the bar V . Pivoted on the bar V by a stud v^8 is a pawl or trip-lever V^2 having a cam-face v^9 adapted to ride against the edge of the plate U^2 . The lever V^2 is formed with a tail-piece v^{10} which carries a laterally projecting pin v^{11} . The pin v^{11} is adapted to be engaged by the toe-piece z of a bent rod Z which is secured in a bearing r^8 on the frame R' by means of the set-screw r^9 . The rod Z is adjustable in its bearing r^8 to set the toe-piece z at different heights. The purpose of this arrangement is to provide means for stopping the machine when the cop or package reaches its predetermined size as hereinafter more fully explained.

The operation of the complete machine is as follows: After the cop-tube f has been placed on the winding-spindle F the yarns y are led up through the tension-devices Q' and thence through the eyes r at the ends of the drop-wires R . From the drop-wires R the yarns are drawn up across the rod R^8 , through the notch e^2 in the thread-guide E and the ends secured in place on the cop-tube. To start the machine the operating-handle K is pressed downwardly to swing the spindle-bearing G over into position above the drive-roll D' . During this movement of the bearing G the bar U connected to its arm g^4 will move upwardly and under the influence of the spring-pressed plunger u' will be swung laterally to engage its latch u^5 with the detent-shoulder v^3 on the bar V . Previous to this the dog-lever W will have been released to allow the carriage H to slide down on the rod h so that the cop-tube f will contact with the drive-roll D' and be rotated therefrom. Before the winding-

spindle starts to rotate there will be more or less slack in the yarns y and consequently the drop-wires R will not be raised immediately to their normal positions in contact 5 with the cross-rod r^6 . Owing to this the bail R^2 is liable to be held in such position that the pawl T , to which it is connected through the lever S and link t , is apt to swing into engagement with the teeth of 10 the wheel T^2 and cause an immediate stopping of the winding-spindle or else a chattering of the pawl against the wheel. To avoid this condition the inclined face v^7 of the 15 detent-block V' is provided to act on the bar U to cause the pawl T to be held away from the ratchet-wheel. This operation is effected through the natural inclination of the operator to hold his hand on the starting-lever K for an instant or more after 20 pressing the lever down. This causes the latch u^5 to ride up on the incline v^7 of the detent-block V' to force the bar U away from the bar V thereby allowing the lever T' to swing downwardly under the influence 25 of gravity to carry the end of the pawl T out of range of the teeth t^8 on the wheel T^2 . Now, when the lever K is released the latch u^5 moves back into engagement with the 30 detent-shoulder v^8 and the two bars U and V are locked together to prevent the spring g^5 from swinging the spindle-bearing G .

During the operation of the machine the spindle F is rotated from the drive-roll D' which contacts first with the surface of the 35 cop-tube f and then with the periphery of the cop as it builds up on the tube. Meanwhile the thread-guide E is reciprocated back and forth along the spindle through its 40 connection with the cam C' and the yarn y is traversed on the cop to dispose it in helical coils in the usual manner well known to those versed in the art. As the winding increases in diameter the spindle F is forced 45 away from the drive-roll D' with the carriage H sliding upwardly on the rod h . The upward movement of the carriage H slides the two bars U and V upwardly while 50 their detents are held in engagement by the plunger-pin u' bearing on the rod U . Any tendency to downward movement of the carriage H is resisted by the lever W dogging on the bar V .

When any one of the yarns y breaks or its 55 supply is exhausted the corresponding drop-wire R will fall through gravity and its finger r^5 will strike against the bail R^2 . This action causes the bail to be tilted to rock the connected levers S, S' which, acting through 60 the link t , will carry the pawl T into engagement with the teeth t^8 on the ratchet-wheel T^2 as shown in Fig. 7. As the wheel T^2 is continuously rotating it moves the pawl T downwardly thereby rocking the lever T' to carry its arm t' against the side 65 of the bar U . This rocking movement of

the lever T' forces the bar U laterally away from the bar V and disengages the latch u^5 from the detent-shoulder v^8 . As soon as the detents u^5 and v^8 are released the spring g^5 will act on the arm g^4 to swing the spindle-bearing G in the direction indicated by the arrow 2, Fig. 4, so that the cop will be removed from contact with the drive-roll D' . During this swinging movement of the spindle-bearing G the break-wheel J' will 75 be carried into engagement with the brake-shoe J and the friction therebetween will cause the rotation of the spindle to be immediately arrested.

The movement of the bar U under the action of the lever T' is very slight, just sufficient to release the latch u^5 from the relatively narrow shoulder v^8 , but as the end of the latch rides out on the beveled face v^5 , during the downward movement of the bar 80 U , it will cause a further separation of the latter from the bar V . That is to say, the bar U will be carried still farther to the left, as viewed in Fig. 7, against the action of the plunger-pin u' . This continued lateral 85 movement of the bar U carries its side against the end of the screw m^6 in the arm m^5 of the lifter-plate M and tilts the latter to raise its edge m above the top of the thread-guide E . Through this action the 90 yarns y are lifted out of the notch e^2 in the guide and are held away from the latter so that as the guide continues to reciprocate it will not carry the yarns with it or interfere in any way with the loose ends. When the 95 machine is started again the plate M drops back into place below the top of the guide E as illustrated in Fig. 7. In threading up the ends it is only necessary to let them rest on the edge m of the plate M and the curved 100 upper edge of the guide E will ride under them and automatically pick them up in the notch e^2 .

As before stated, the rod Z is adjusted in its bearing r^8 to bring its toe z to a height 110 proportionate to the size of the package desired. Now, as the carriage H rides up on the rod h with the growth in the diameter of the winding, the bar V sliding upwardly therewith will eventually cause the pivoted 115 trip-lever V^2 to be brought into position for its pin v^{11} to be engaged by the toe z on the rod. This engagement acts to rock the lever V^2 to cause its cam-face v^9 acting on the edge of the plate U^2 to pry the bar U away 120 from the bar V . Through this action the detents u^5 and v^8 are disengaged to release the bar U and the other elements of the mechanism then act to arrest the winding 125 operation as before explained.

Particular attention is called to the arrangement of the means for supporting the spindle-bearing G to adapt the cop to swing away from the drive-roll in a substantially horizontal direction. It will be noted that 130

the bearing G is pivoted on an axis above the axis of the drive-roll D' so that in releasing the cop from contact with the roll the bearing G is moved laterally with respect to the vertical plane passing through the axis of the spindle and roll. That is to say, it is not necessary to lift the spindle and cop bodily away from the drive-roll, but only to swing them to one side of their operative position. Heretofore in machines of this type it has been the usual practice to disengage the cop or package from the drive-roll by lifting it vertically upward therefrom. This method of operation entails the raising of a mass of considerable weight consisting of the spindle, its bearing and the other supporting mechanism, besides the package itself. On account of this a relatively great amount of energy is required to operate the stopping-mechanism of the machine and usually the operating-means must be connected to a going part of the machine. In some cases springs or weights are employed, but these must be of great tension in the one case or very heavy in the other and are objectionable on this account because considerable strength is required to overcome their force in starting the machine. The most serious objection to such arrangements, however, is that the cop or package cannot be stopped quickly. That is to say, it requires not only considerable energy, but also a relatively longer time to overcome the inertia of the parts which must be lifted in raising the cop off from the drive-roll and hence its rotation cannot be arrested as quickly as desirable. With the present arrangement it is only necessary to swing the winding-spindle to one side of its normal position and very little energy is required since the weight of the spindle, its bearing and the cop always remains suspended from above. For this reason a light, quick-acting spring can be employed for operating the spindle-bearing, and the stopping operation can be effected without other power and with great speed. This quick action of the stopping-devices is of utmost importance, because if the rotation of the cop is not arrested very promptly the ends of the broken yarns will run into the package. If the broken ends are lost in the winding it requires considerable effort to find and pull them off again and sometimes required for properly piecing up. For this reason the winding will often be defective with the ends tied together in "bunch" knots and therefore the ultimate value of the product is impaired. The present invention overcomes these defects usual to drum-winders and in addition shows other improvements both in the simplification of the mechanism of the machine and the provisions for ease and despatch in its operation. The winding

is controlled through sensitive devices which act immediately upon the release of tension on the yarn to arrest the rotation of the package and to also render the thread-guide inoperative. By providing for greater ease and facility in piecing up the quality of the winding is improved and an increased production of the machine made possible.

Various modifications might be made in the form and arrangement of our new mechanism without departing from the spirit or scope of the invention;

Therefore, without limiting ourselves to the exact construction shown and described, what we claim is:

1. In a winding machine, the combination with the reciprocating thread-guide and rotating drive-roll, of a winding-spindle for supporting the cop to adapt it to be driven from the roll, a bearing for the spindle pivoted on an axis arranged above the roll, said bearing arranged to recede from the drive-roll with a straight-line movement in a plane passing through the axis of the roll and means to swing said spindle-bearing laterally with respect to the vertical plane of the axis of the roll to remove the cop from contact with the roll.

2. In a winding machine, the combination with the reciprocating thread-guide and rotating drive-roll, of a carriage adapted to move away from the drive-roll in a substantially vertical direction during the growth in diameter of the cop, a bearing supported on the carriage to adapt it to be moved in a substantially horizontal direction toward and away from the roll, and a spindle rotatably mounted in said bearing and adapted to support the cop to normally maintain it in contact with the roll.

3. In a winding machine, the combination with the reciprocating thread-guide and rotating drive-roll, of a winding-spindle for supporting the cop to adapt it to be driven from the roll, means for supporting the spindle to move away from the roll in a substantially vertical direction during the growth in diameter of the cop, and means to move said spindle in a substantially horizontal direction to carry the cop out of contact with the roll to arrest its rotation.

4. In a winding machine, the combination with the reciprocating thread-guide and rotating drive-roll, of a winding-spindle for supporting the cop to adapt it to be driven from the roll, a carriage arranged to move upwardly away from the drive-roll, and a bearing for the winding-spindle pivoted on the carriage to adapt it to swing at substantially right-angles to the direction of movement of the carriage to remove the cop from contact with the drive-roll.

5. In a winding machine, the combination with the reciprocating thread-guide and rotating drive-roll, of a carriage adapted to

move away from the roll in a substantially vertical direction, a bearing pivoted on the carriage above the roll to adapt it to swing across the vertical plane of the axis of the 5 roll, and a winding-spindle mounted to rotate in said bearing and adapted to support the cop in contact with the roll.

6. In a winding machine, the combination with the reciprocating thread-guide and rotating drive-roll, of a winding-spindle for supporting the cop during the winding thereof, means for supporting the spindle to adapt the cop to contact with the roll, and to move vertically away from the roll 10 as the cop increases in diameter, a brake-wheel on the spindle, a brake-shoe adapted to engage the brake-wheel, and means to move the spindle in a substantially horizontal direction to carry the cop out of contact 15 with the roll and to concurrently engage the brake-wheel with the brake-shoe to arrest the rotation of the spindle.

7. In a winding machine, the combination with the reciprocating thread-guide and rotating drive-roll, of a winding-spindle for supporting the cop to adapt it to be driven from the roll, means for supporting the spindle to adapt it to move upwardly away from the roll during the growth in diameter 25 of the cop, braking-means adapted to act on the spindle, and means to move the spindle in a direction substantially perpendicular to its upward movement to carry the cop away from contact with the roll and to currently 30 actuate the braking-devices to arrest the rotation of the spindle.

8. In a winding machine, the combination with the reciprocating thread-guide and rotating drive-roll, of a winding-spindle on which the cop is supported to adapt it to be driven from the roll and to recede therefrom, with the growth in the winding, a bearing for the spindle pivoted on an axis arranged above and parallel with the axis 40 of the roll, means to swing said bearing on its pivot to move the spindle laterally, independently of its main movement away from the roll and positive detent-means for normally maintaining the bearing in position 45 with the cop in contact with the roll.

9. In a winding machine, the combination with the reciprocating thread-guide and rotating drive-roll, of a winding-spindle on which the cop is supported to adapt it to be driven from the drive-roll and to recede vertically therefrom with the growth in the winding, a pivotally mounted bearing for the spindle, means to swing said bearing to move the spindle in a direction substantially 55 perpendicular to its vertical receding movement to carry the cop away from contact with the drive-roll, detent-means to normally maintain the bearing in position with the cop in contact with the drive-roll, and means controlled by the tension on the yarn 60

delivering to the winding-spindle to release the detent-means when the yarn breaks or becomes exhausted.

10. In a winding machine, the combination with the reciprocating thread-guide and rotating drive-roll, of a winding-spindle on which the cop is supported to adapt it to be rotated from the drive-roll and to recede vertically therefrom with the growth in the winding, a pivoted bearing for supporting the spindle to adapt the cop to swing horizontally into and out of contact with the drive-roll independently of the vertical receding movement of the spindle, a spring to swing the bearing to carry the cop away 85 from the roll, detent-means for normally maintaining the bearing in position against the action of the spring, and devices for releasing the detent-means upon the breakage or exhaustion of the yarn. 85

11. In a winding machine, the combination with the reciprocating thread-guide and rotating drive-roll, of a winding-spindle for supporting the cop, a bearing for supporting the spindle to adapt the cop to be carried into and out of contact with the roll, a carriage for supporting the spindle-bearing to adapt it to recede from the roll as the cop increases in diameter, a spring for normally operating the spindle-bearing 95 to remove the cop from contact with the roll, a detent-member connected with the spindle-bearing, a second detent-member connected with the carriage, and means to lock the detent-members in engagement to 100 normally maintain the cop in contact with the roll.

12. In a winding machine, the combination with the thread-guide, drive-roll and winding-spindle, of a bearing for the spindle adapted to be operated to carry the cop into and out of engagement with the roll, a spring for operating the bearing to remove the cop from contact with the roll, detent-means for holding the bearing against the 105 action of the spring, means to release the detent-means, a rotating element adapted to operate the releasing-means for the detents, and means to carry the releasing-means out of range of the rotating element during the 110 operation of engaging the detent-means. 115

13. In a winding machine, the combination with the thread-guide, drive-roll and winding-spindle, of a bearing for the spindle adapted to be operated to carry the cop 120 into and out of engagement with the roll, a spring for operating the bearing to remove the cop from engagement with the roll, detent-means adapted to be engaged to maintain the bearing against the action of 125 the spring, a trip-lever for moving one detent-member to release it from the other, a rotating element, a pawl adapted to be engaged with said rotating element to operate the trip-lever, and means to move one 130

- of the detent-members during its engagement with the other to cause the trip-lever to be operated to carry the pawl out of range of action of the rotating element.
5. 14. In a winding machine, the combination with the thread-guide, drive-roll and winding-spindle, of a bearing for the spindle adapted to be operated to carry the cop into and out of engagement with the roll, a spring for operating the bearing to remove the cop from engagement with the roll, a carriage for supporting said bearing to adapt the spindle to recede from the roll during the growth in the winding, a detent-member connected to the bearing, a second detent-member connected with the carriage, means for locking said detent-members together to prevent movement of the spindle-bearing with respect to the carriage, and means adapted to be operated when the carriage reaches a predetermined position to release the locking-means on the detent-members.
15. 15. In a winding machine, the combination with the thread-guide, drive-roll and winding-spindle, of a bearing for the spindle adapted to be operated to carry the cop into and out of engagement with the roll, a spring for operating the bearing to remove the cop from engagement with the roll, a carriage for supporting said bearing to adapt the spindle to recede from the roll during the growth in the winding, a detent-member connected to the bearing, a second detent-member connected with the carriage, means to lock said detent-members together to prevent movement of the spindle-bearing with respect to the carriage, means to pry said detent-members apart to release the locking-means, and means adjustable in position to engage the prying-means after the carriage has been moved a predetermined distance.
16. 16. In a winding machine, the combination with the thread-guide, drive-roll and winding-spindle, of a bearing for the spindle adapted to be operated to carry the cop into and out of engagement with the roll, a spring for operating said bearing to remove the cop from contact with the roll, a carriage for supporting the bearing to adapt the spindle to recede from the roll with the increase in diameter of the cop, a longitudinally slideable bar connected with the bearing, a second bar arranged parallel thereto and connected to the carriage to slide therewith, a latch on one bar adapted to engage a detent-shoulder on the other bar, and means to force one bar toward the other to engage the latch with the detent-shoulder.
17. 17. In a winding machine, the combination with the thread-guide, drive-roll and winding-spindle, of a bearing for the spindle adapted to be operated to carry the cop into and out of engagement with the roll, a spring for operating said bearing to remove the cop from contact with the roll, detent-members adapted to be locked together to hold the spindle-bearing against the action of the spring, a trip-lever engaging one of the detent-members, a rotating element, means on the trip-lever to engage the rotating element to operate the lever, and means on one of the detent-members to move the other member to allow the trip-lever to be carried into position to free the engaging-means from the rotating element when said detent-members are being locked together.
- In testimony whereof we affix our signatures in presence of two witnesses.
- FESTUS S. RAND.
GEORGE N. TAYLOR.
- Witnesses:
HERBERT K. ALLARD,
GEORGE A. WHITE, Jr.

Washington, D. C."

It is hereby certified that the assignee in Letters Patent No. 1,205,565, granted November 21, 1916, upon the application of Festus S. Rand, of Providence, and George N. Taylor, of East Providence, Rhode Island, for an improvement in "Winding-Machines," was erroneously described and specified as "Universal Winding Company, of Portland, Maine, a corporation of Maine," whereas said assignee should have been described and specified as *Universal Winding Company, of Boston, Massachusetts, a corporation of Massachusetts* said corporation being assignee by *mesne assignments* of the entire interest in said invention, as shown by the records of assignments in this office; and that the said Letters Patent should be read with this correction therein that the same may conform to the record of the case in the Patent Office.

Signed and sealed this 19th day of December, A. D., 1916.

[SEAL.]

R. F. WHITEHEAD,
Acting Commissioner of Patents.
